UNITED STATES PATENT OFFICE.

PAUL E. SAEHRENDT, OF BROOKLYN, NEW YORK.

POCKET ADDING-MACHINE.

1,078,385.

Specification of Letters Patent. Patented Nov. 11, 1913.

Application filed December 10, 1912. Serial No. 735,890.

To all whom it may concern:

Be it known that I, PAUL E. SAEHRENDT, a citizen of the United States, residing at Brooklyn, in the county of Kings and State 5 of New York, have invented certain new and useful Improvements in Pocket Adding Machines, of which the following is a specification.

This invention relates to adding machines, 10 and more particularly to pocket adding machines, the object of the invention being to provide a simple, compact and comparatively inexpensive mechanism of this character easily operated and accurate in its calculations, and is in part an improvement 15 upon the apparatus shown and described in the patent issued to me on August 13, 1912, No. 1,035,475.

In the drawings accompanying and forming part of this specification, Figure 1 is 20 a top view of this improved adding machine with a part of the top of the casing broken away; Fig. 2 is a cross-sectional view of the mechanism shown in Fig. 1, taken in line 25 2-2, Fig. 1; Fig. 3 is a cross-sectional view of a part of the mechanism, taken on line 3-3, Fig. 1; Figs. 4, 5, 6, 7, 8, 9, 10 and 11 are mostly perspective detail views illustrating the mechanism for returning the dials to 30 their zero positions; Fig. 12 is a detail view illustrating the mechanism for returning the dial 42 to its zero position; Fig. 13 is a detail view illustrating the key operated means for operating the dials; Fig. 14 is a sectional view through the dials and illustrating in 35 section the parts shown in Figs. 2 and 3; and Fig. 15 is a detail view of the clutch members for the dials 40 and 41.

Similar characters of reference indicate 40 corresponding parts throughout the figures of the drawings.

The operating mechanisms are carried by 45 a suitable casing shown herein as a circular body 2 having a bottom plate 3 and a top plate 4, in which casing all of the operating mechanisms are located, the keys only projecting from the top of the casing. Supported on the bottom 3 is a supplemental bottom or plate 5, on which is pivotally

supported on a centrally located pin 6 a 50 rotary disk 7. Pivots secured to the supplemental bottom plate 5, as at 8, is a series of levers 9, nine in number. Each of these levers has a bent end 9' and carries at its inner end a headed pin 10, which pins project into slots 11 of the rotary disk 7. The headed pins are located at various distances from the pivotal points 8 of the levers so as to vary the leverage of the levers 9, and these headed pins or studs 10 revolve the 60 disk 7 on the shifting of the levers 9. Each of these slots 11 is cut laterally to form a clearance space 11' and is notched, as at 11'', for the reception of the stud or pin of its lever, so that when the stud at the end 65 of the lever has rotated the disk it is, by means of this notch 11'', locked in the extreme outer portion of the slot so that the disk can go no farther. In other words, as each lever 9 is operated the stud thereof engages the inclined wall 9'' and shifts the 70 disk 7 until the pin 10 is received in the notch 11'', while the remaining pins of the levers which have not been operated by the keys remain unaffected by reason of the 75 clearance space 11' which permits the movement of the disk 7 without affecting the position of the pins. The clearance space of each successive lever, from 1 to 9, is longer than that of its predecessor by reason of 80 the fact that each successive lever has a greater movement than the preceding lever, and therefore this must be provided for by giving increased length to each succeeding slot, so that the stud 10 of any lever not operated by this key will not be affected by 85 movement of the disk.

In my prior patent referred to the connection between the disk and the levers was different from that shown in the present 90 case, and the means for operating the levers by the keys was likewise different, the present improvement having some advantages over my former improvement. In that case the levers were operated by cams operated 95 by or carried by the keys. In the present case I have done away with cams entirely.

Suitable keys 12 are provided, one for

each lever, and as there are nine levers nine keys are shown and marked on the heads thereof with the characters 1 to 9. Each of the key rods 13 is guided within a slotted 5 casing 14, each rod being returned to its normal position by means of a spring 15 located between the end of the rod and the bottom of the casing. Each rod is slotted at its lower end, as at 16, and into the slot 10 extends the end 17 of a rocking lever 18 pivotally supported by a post 19 adjacent to the slotted sleeve 14 and having a depending portion 20 adapted to engage the adjacent lever 9, so that as each key is depressed 15 it will rock the rocking lever and thus operate the lever 9. The rocking lever 18 is provided with a cam projection 21 having an inclined or cam formed under-surface 22 adapted, when the key is depressed, to engage a sliding tooth 23 which 20 is provided with an upturned flange 24 for engagement by the inclined surface of the projection. This tooth is slidably supported so that when pushed forward on the 25 depression of the key as the master gear hereinafter referred to is rotated it will engage the teeth thereof and act as a detent to lock the master gear, thus preventing, should any one of the keys be hit hard, the 30 flying around or further rotation more than the required number of teeth according to the push rod that is operated. This detent is retracted by a spring 26. In other words, as key No. 1 operates the master gear one 35 tooth this detent would prevent the master gear from moving more than one tooth, while as key No. 9 operates the master gear nine teeth it would prevent the movement of the gear more than the required nine teeth. 40 Thus it will be observed that as each push rod is operated the disk operating lever which is controlled thereby will be shifted so as to shift the rotary disk 7 the required distance according to the leverage of the 45 lever which is operated. The greater the distance between the pins 10 and the pivotal points 8 of these levers 9 the greater will be the rotary movement of the disk 7. After each push rod is shifted it is returned by the 50 spring 15 carried by the sleeve which guides the push rod. When the key is released and returned by its spring to its normal position the rotary disk will be swung back into its original position by means of a 55 spring 25, one end of which is secured to a stud 25' carried on the underside of the disk 7 and which projects through a slot 25''' in the bottom plate 5 while the other end is secured to a fixed point 25''. At the 60 same time the key operated levers 9 will be returned to their normal positions by means of springs 9''. For limiting the return movement of the disk the pin 25' cooperates with the end of the slot 25''', thus prevent-

ing the rotary disk being swung back beyond its original position by the spring 25. 65

On top of the rotary disk 7 is the master gear 27 mounted loosely on the pin 6. Secured to the rotary disk 7 is a spring pressed pawl 28, which is forced into the teeth of 70 this gear by means of a spring 29, so that when the disk 7 is rotated forward in the manner hereinbefore indicated the master gear is also rotated with it by means of the pawl 28 just referred to. Another spring 75 pressed pawl 30 is also provided and properly positioned and pressed into engagement with the teeth of the master gear by means of a spring 31. This pawl merely rides over the teeth of the master gear when the 80 same is turned by the pawl 28 until the gear comes to a stop, at which time the pawl 30 prevents the return movement of the gear 27 with the rotary disk 7 when the same is shifted backward by means of its spring 25, 85 thus holding the master gear in its advanced position, the pawl 28, on the pulling backward of the rotary disk 7 by its spring 25, at this time riding over the teeth of the master gear in a manner which will be 90 readily understood. Thus it will be observed that by means of these two pawls the master gear 27 may be advanced with the rotary disk 7, but its advanced position not affected by the return or backward 95 movement of the rotary disk 7 through the medium of its spring 25.

The adding mechanism comprises three dials 40, 41 and 42, three pinions 43, 46 and 47, a pair of gears 44 and 45 a pair of 100 Geneva devices 48 and 49, and three sets of tooth-formed sliding clutch members 50, 51 and 52, one for each dial. The form of the sliding clutch members for the dial 42 is shown more clearly in Fig. 12, while that 105 for the dials 40 and 41 is shown more clearly in Figs. 14 and 15, and as the last two are duplicates a description of that for the dial 40 will suffice. The pinion 43 meshes with the master gear 27, while a Geneva device 110 48 revolves with such pinion 43 when the clutch members are in engagement. The dial 40 and its hub 48', to which it is fixed, see Fig. 14, is loosely mounted for sliding movement on a pin 40'' and on the bushing 115 40''' of the pinion 43, through which bushing the pin 40'' extends. On the interior of the hub 48' of the dial 40, to which the Geneva device 48 is fixed, is formed or located a toothed clutch member 50', which 120 thus slides or moves up and down with the dial 40, see Fig. 15. Secured to the bushing 40''' of the gear 43 is the companion clutch member comprising in the present instance a fixed pin 50'' adapted to engage the teeth 125 of the clutch member 50', such engagement being maintained by means of a spring 60 which presses the sliding tooth formed

clutch member 50' into engagement with the pin 50'', so that when the two clutch members are in engagement the dial and its Geneva device will rotate with the pinion 43 and when out of engagement the dial 40 and its Geneva device 48 will be free for rotation independently of the gear 43 and also independently of the pinion 46 when the sliding clutch member is depressed in the manner hereinafter described.

The toothed clutch member 50' is provided with ten teeth, as are also the other toothed clutch members of the other two dials. Thus the pinion 43, Geneva device 48 and dial 40 turn as one unit together when the two clutch members 50' and 50'' are in engagement. The Geneva device 48, like the Geneva device 49, is a disk with one tooth cut in it, so that in one complete turn this Geneva device 48 engages only once with its gear 46. This gear 46, like the gear 47, has the lower half of every other tooth cut away so that when the Geneva device engages it it turns the gear 46 two teeth. As pinion 43 has ten teeth and its Geneva device 48 one tooth, and gear 46 has ten teeth on its upper half and is turned two teeth on each complete revolution of pinion 43, and as gear 46 meshes with gear 44, which has twenty teeth and is connected with the Geneva device 49 fixed to the hub of the dial 41 by clutch members 51' and 51'' similar to those hereinbefore described in connection with dial 40, it follows that the ratio between the revolutions of dials 40 and 41 is one to ten. The same is true also of dials 41 and 42, the ratio being exactly the same, and therefore need not be further described. The ratio between the first and third dials 40 and 42 is therefore one to one hundred.

As hereinbefore stated, the clutch members of the third dial 42 are shown in Fig. 12, in which the sliding tooth-formed member 52' is normally held in engagement with a pin 52'' carried by the member 99 by means of a spring 52''. Thus it will be observed that on the shifting forward of the rotary disk by the levers through the medium of the keys in the manner hereinbefore described the several dials are operated in the manner herein set forth. For returning the dials to their zero positions suitable mechanism is provided, comprising a key 61, marked 0, the key rod 61' of which is suitably supported in a tubular slotted bushing or sleeve 62 and is maintained in its normal position by a spring 63, see Fig. 8. On depressing this push rod its stem will engage a lever 64, which is pivoted as at 65 to form a bell-crank with the longer arm 64' of the lever extending through the slotted casing of the stem, so that as this bell-crank lever is rocked on its pivot its short end 64'' will rock a rocking device 67 carried by a stud 68, and this rocking device 67 will in turn

engage a cam-faced member 69 pivotally supported in position to be swung in one direction by this rocking device 67 and returned to its normal position by a spring 70. The forward end of this member 69 is provided with a projection 71, the top face of which is inclined, as at 72, so as to engage and raise a projection 73 carried by a rock shaft 74 suitably supported, and which rock shaft carries three clutch shifters 75, 76 and 77, one for each sliding clutch member 50', 51' and 52'. These clutch shifters partly encircle grooves 80 in the hubs of the sliding or toothed clutch members so that the same may rotate relatively to the clutch shifters, but when the projection carried by the rock shaft is raised the clutch shifters will depress the toothed clutch members against their springs and thus separate them from their respective pins 50'', 51'' and 52'' hereinbefore described. The separation of the clutch members 50' and 51' from their pins also carries the Geneva devices 48 and 49 below and free of the gears 46 and 47, so that the dials may now be returned to their zero positions. The projection of the rock shaft having been raised by the member 69 and the dials returned to their zero positions the projection is released so as to permit the toothed clutch members to return by means of their springs into position to engage the pins 50'', 51'' and 52''.

The return of the dials to their zero positions is accomplished by means of a sliding plate 90, see Fig. 5, suitably supported on upright posts 91. This plate is provided with three projections 92, each adapted to engage a heart-shaped cam member 99 at any position in which they may be at the time it is desired to return the dials to their zero positions. These members 99 are in the form of eccentrics, one secured to each dial hub. This plate 90 is shifted forward on the depression of the zero marked key by means of the longer arm 64' of the bell-crank lever 64 by reason of the fact that this longer portion 64' of the lever engages one arm 93 of a bell-crank lever the opposite arm 94 of which actuates a rocking device 95, which engages a pin 96 of the plate 90 and shifts it forward, whereupon its projections 92 engage the heart-shaped cam members, rotating them and their dials, provided of course the toothed clutch members are separated by means of the clutch shifter mechanism from the pin clutch members hereinbefore described, to the zero positions of such dials. Each of the heart-shaped members is provided at its rear with a notch 97 which, as the dials are brought to their zero positions, receive the projections 92 of the sliding plate and so hold these cam-shaped members from further movement, at which time the co-operating tooth-formed clutch members will return into position to engage the clutch

pins, whereby further movement of the dials except by manipulation of the proper keys is prevented. The sliding plate 90 will be returned to its normal position by means of 5 suitable springs 98, to be again shifted in the manner just described.

It will be understood that each dial is shifted according to the distance traveled by the key operated lever. In other words, one 10 key will shift its lever a short distance while another key will shift its lever a comparatively great distance, and consequently the dials will be rotated according to the distance of travel of the several levers.

15 I claim as my invention:

1. In a pocket adding machine, the combination of adding mechanism including a plurality of dials, a master gear for controlling the movements thereof and means for 20 rotating said gear and comprising a rotary disk, a series of pivotally connected levers, a series of keys corresponding in number with the number of levers and rocking devices supported in position to be operated 25 by the keys for shifting said levers thereby to rotate the disk.

2. In a pocket adding machine, the combination of adding mechanism including a plurality of dials, a master gear for controlling 30 the movements thereof and means for rotating said gear and comprising a rotary disk, a series of pivotally connected levers, a series of keys corresponding in number with the number of levers and rock- 35 ing devices supported in position to be operated by the keys for shifting said levers thereby to rotate the disk, the organization being such that each lever will be shifted a distance different from all of its companion 40 levers.

3. In a pocket adding machine, the combination of adding mechanism including a plurality of dials, a master gear for controlling the movements thereof and means 45 for rotating said gear and comprising a rotary disk, a series of pivotally connected levers, a series of keys corresponding in number with the number of levers, rocking devices supported in position to be operated 50 by the keys for shifting said levers thereby to rotate the disk and a detent actuated by each of the keys for engaging said master gear.

4. In a pocket adding machine, the combination of adding mechanism including a 55 plurality of dials, a master gear for controlling the movements thereof and means for rotating said gear and comprising a rotary disk, a series of pivotally connected 60 levers, a series of keys corresponding in number with the number of levers, rocking devices supported in position to be operated by the keys for shifting said levers thereby to rotate the disk and a detent actuated by 65 each of the keys for engaging said master

gear, the organization being such that each lever will be shifted a distance different from all of its companion levers.

5. In a pocket adding machine, the combination of adding mechanism including a plurality of dials and means for controlling the movements thereof and including a rotary disk, a series of pivotally connected levers coöperating with said disk, a series of keys corresponding in number with the 70 number of levers and rocking devices in position to be operated by the keys for shifting said levers thereby to rotate the disk.

6. In a pocket adding machine, the combination of adding mechanism including a plurality of dials and means for controlling the movements thereof and including a rotary disk, a series of pivotally connected levers coöperating with said disk, a series of keys corresponding in number with the 75 number of levers and rocking devices in position to be operated by the keys for shifting said levers thereby to rotate the disk, the organization being such that each key will shift its lever a distance different from 80 that of its companion keys.

7. In a pocket adding machine, the combination of adding mechanism including a plurality of dials and means for controlling the movements thereof and including a rotary disk, a series of pivotally connected levers coöperating with said disk, a series of keys corresponding in number with the 85 number of levers and pivotally supported devices in position to be operated by the keys for shifting said levers thereby to rotate the disk, the organization being such that each key will shift its lever a distance different from that of its companion keys, and springs for holding said levers in engagement with said pivotally supported devices and for returning said levers to their 90 normal positions.

8. In a pocket adding machine, the combination of adding mechanism including a plurality of dials and means for controlling the movements thereof and including a rotary disk, a series of pivotally connected levers coöperating with said disk, a series of keys corresponding in number with the 100 number of levers, springs for returning said keys to their normal positions, and pivotally supported devices in position to be operated by the keys for shifting said levers thereby to rotate the disk, the organization being such that each key will shift its lever a distance different from that of its companion keys.

9. In a pocket adding machine, the combination of adding mechanism including a 110 plurality of dials and means for controlling the movements thereof and including a rotary disk, a series of pivotally connected levers, a series of keys corresponding in number with the number of levers and 115

120

125

130

means operated by the keys for shifting said levers thereby to rotate the disk, the organization being such that each key will shift its lever a distance different from that of its 5 companion keys, said disk and levers having one pins and the other slots for the reception of said pins, said slots extending laterally relatively to the disk.

10. In a pocket adding machine, the combination of adding mechanism including a plurality of dials and means for controlling the movements thereof and including a rotary disk, a series of pivotally connected levers, a series of keys corresponding in 15 number with the number of levers and means operated by the keys for shifting said levers thereby to rotate the disk, the organization being such that each key will shift its lever a distance different from that of its 20 companion keys, said disk and levers having one pins and the other slots for the reception of said pins, said slots extending laterally relatively to the disk and having at 25 one part notches for the reception of said pins.

11. In a pocket adding machine, the combination of adding mechanism including a plurality of dials and means for controlling the movements thereof and including a rotary disk, a series of pivotally connected levers, a series of keys corresponding in 30 number with the number of levers and means operated by the keys for shifting said levers thereby to rotate the disk, the organization being such that each key will shift its lever a distance different from that of its 35 companion keys, said disk and levers having one pins and the other slots for the reception of said pins, said slots extending laterally relatively to the disk and each succeeding slot having greater length than the preceding slot.

12. In a pocket adding machine, the combination of adding mechanism including a plurality of dials and means for controlling the movements thereof and including a rotary disk, a series of pivotally connected levers, a series of keys corresponding in 45 number with the number of levers and means operated by the keys for shifting said levers thereby to rotate the disk, the organization being such that each key will shift its lever a distance different from that of its 50 companion keys, said disk and levers having one pins and the other slots for the reception of said pins, said slots extending laterally relatively to the disk and having at 55 one part notches for the reception of said pins and each succeeding slot having greater 60 length than the preceding slot.

13. In a pocket adding machine, the combination of adding mechanism including a plurality of dials and means for controlling the movements thereof and including a rotary disk, a series of pivotally connected le- 65

vers, a series of keys corresponding in number with the number of levers and means operated by the keys for shifting said levers thereby to rotate the disk, the organization being such that each key will shift its lever a distance different from that of its companion keys, said levers having pins and said disk having laterally extending slots each of greater length than its preceding slot and also having a notch for the reception of said 75 pins.

14. In a pocket adding machine, the combination of adding mechanism including a plurality of dials, means for controlling the movements thereof and including a rotary 80 disk, a series of pivotally connected levers coöperating with said disk, a series of keys corresponding in number with the number of levers, means operated by the keys for shifting said levers thereby to rotate the 85 disk, the organization being such that each key will shift its lever a distance different from that of its companion keys, a pair of clutch members for connecting each of the dials with its controlling mechanism, one 90 shiftable relatively to the other, means for shifting said shiftable clutch members, and means for returning the dials to their zero positions.

15. In a pocket adding machine, the combination of adding mechanism including a plurality of dials, means for controlling the movements thereof and including a rotary disk, a series of pivotally connected levers coöperating with said disk, a series of keys 100 corresponding in number with the number of levers, means operated by the keys for shifting said levers thereby to rotate the disk, the organization being such that each key will shift its lever a distance different 105 from that of its companion keys, a pair of clutch members for connecting each of the dials with its controlling mechanism, one shiftable relatively to the other, means for shifting said shiftable clutch members, and 110 means for returning the dials to their zero positions, the means for shifting the clutch members and returning the dials comprising a single key operated mechanism.

16. In a pocket adding machine, the combination of adding mechanism including a plurality of dials, means for controlling the movements thereof and including a rotary disk, a series of pivotally connected levers coöperating with said disk, a series of keys 115 corresponding in number with the number of levers, means operated by the keys for shifting said levers thereby to rotate the disk, the organization being such that each key will shift its lever a distance different 120 from that of its companion keys, a pair of clutch members for connecting each of the dials with its controlling mechanism, one shiftable relatively to the other and one comprising a pin and the other a toothed mem- 125 130

ber, means for shifting said shiftable clutch members, and means for returning the dials to their zero positions.

17. In a pocket adding machine, the combination of adding mechanism including a plurality of dials, cams connected therewith, means for controlling the movements thereof and including a rotary disk, a series of pivotally connected levers coöperating with said disk, a series of keys corresponding in number with the number of levers, means operated by the keys for shifting said levers thereby to rotate the disk, the organization being such that each key will shift its lever a distance different from that of its companion keys, a pair of clutch members for connecting each of the dials with its controlling mechanism, one shiftable relatively to the other and one comprising a toothed member, a clutch shifter for actuating the shiftable clutch members simultaneously, a sliding plate for engaging the cams simultaneously thereby to return the dials to their zero positions when the clutch members are disengaged, and means for shifting said plate and actuating said clutch shifter.

18. In a pocket adding machine, the combination of adding mechanism including a plurality of dials each having an eccentrically formed cam connected therewith, means for controlling the movements of said dials and including a pair of clutch members, means for separating the clutch members and means for rotating said cams to return the dials to their zero positions on the separation of said clutch members.

19. In a pocket adding machine, the combination of adding mechanism including a plurality of dials, a cam connected with each, means for controlling the movements of said dials and including a pair of clutch members, a clutch shifter for separating the clutch members, and means for rotating the cams and thereby the dials to return them to their zero positions, said means comprising a shiftable member and key operated mechanism for shifting said member and the clutch shifter simultaneously.

20. In a pocket adding machine, the combination of adding mechanism including a plurality of dials, a cam connected with each, means for controlling the movements of said dials and including a pair of clutch members for each of the dials, a clutch shifter for separating the clutch members, means for rotating the cams and thereby the dials to return them to their zero positions, said means comprising a sliding plate and key operated mechanism for shifting said plate, and means operated by the same key for simultaneously shifting the clutch shifter, each of said cams having a notch coöperating with said sliding plate when the dials are in their zero positions.

21. In a pocket adding machine, the com-

bination of adding mechanism including a plurality of dials, means for controlling the movements thereof and including a pair of clutch members for each dial, one comprising a toothed sliding member connected with the dial, a cam connected with said toothed member, a rotary disk, a series of pivotally connected levers for operating said disk, a series of keys corresponding in number with the number of levers, means operated by the keys for shifting said levers thereby to rotate the disk, the organization being such that each key will shift its lever a distance different from that of its companion keys, a master gear rotated by said disk and a detent for engaging said master gear, one for each key and operated by said keys, a clutch shifter for each of the sliding clutch members, a sliding plate coöperating with the cams for returning them and thereby the dials to their zero positions, and key operated mechanism for shifting said clutch members and said sliding plate simultaneously.

22. In a pocket adding machine, the combination of adding mechanism including a plurality of dials, a master gear for controlling the movements thereof, means for rotating said gear and comprising a rotary disk carrying a pawl, a series of pivotally connected levers coöperating with said disk, said disk and levers having slots and pins, each pin projecting into a slot, a series of keys corresponding in number with the number of levers, and rocking devices operated by the keys for shifting said levers thereby to rotate the disk, the organization being such that each key will shift its lever a distance different from that of every other key.

23. In a pocket adding machine, the combination of adding mechanism including a plurality of dials, a master gear for controlling the movements thereof, means for rotating said gear and comprising a rotary disk carrying a pawl, a series of pivotally connected levers coöperating with said disk, said disk and levers having slots and pins, each pin projecting into a slot, a series of keys corresponding in number with the number of levers, rocking devices operated by the keys for shifting said levers thereby to rotate the disk, the organization being such that each key will shift its lever a distance different from that of every other key, and means for returning said dials to their zero positions.

24. In a pocket adding machine, the combination of adding mechanism including a plurality of dials, a master gear for controlling the movements thereof, means for rotating said gear and comprising a rotary disk carrying a pawl, a series of pivotally connected levers coöperating with said disk, said disk and levers having slots and pins,
